CAR STOP

Delmar B. Finch, Montgomery, W. Va.

Application December 28, 1938, Serial No. 248,126

5 Claims. (Cl. 104—258)

The invention relates to improvements in car stops or track dogs for use with mine and other cars to provide a safety device applicable at will to a rail and operable to act as a stop for the purpose of preventing cars from rolling or coasting from predetermined positions to other points hazardous to property or life.

The invention aims to provide a device of the class in question which is simple, safe, inexpensive, readily portable and adequate, which may be attached to rails of more than one size, which can be attached securely in position on the rail without the use of tools other than a hammer, axe or piece of equipment with which to apply force to the clamping mechanism, which can be operated quickly and easily to operative position or to idle position, in the latter of which the track is clear, which may be thus operated without the operator reaching under the car, which may be rendered operative and inoperative without removal from the rail, which can be attached to the rail or detached therefrom while the cars are occupying the track without hazard to the person attaching or detaching the same, and which can be used between the front and rear wheels of a car to act as a stop in both directions.

With the foregoing in view, the invention resides in the novel subject matter hereinafter described and claimed, description being accomplished by reference to the accompanying drawing.

Figure 1 is a top plan view showing the device attached to a rail.

Figure 2 is a longitudinal sectional view partly in elevation as indicated by line 2—2 of Figure 1.

Figure 3 is an end elevation as indicated by the arrow 3 of Figure 2.

A preferred form of construction has been illustrated and will be rather specifically described, with the understanding, however, that within the scope of the invention as claimed, variations may be made.

A horizontally elongated base member 5 is provided to extend under a rail 6, said base member being provided at one end with hooks 7 to engage one edge of the rail base and being provided at its opposite end with a longitudinal slot 8. Near the inner end of this slot, the base member 5 is provided with a rigid upstanding abutment 9.

A slide member 10 rests on the base member 5 and is provided with angular guide flanges 11 slidably embracing the longitudinal edges thereof. The inner end of this slide member 10 is adapted to abut an edge of the rail base to coact with the hooks 7 in securing the device in place, and said inner end is provided with suitable projections 12

to overlie said base. The member 10 is provided with two upstanding ears 13 between which a wheel stop 14 is pivoted by means of a bolt or the like 15. I have shown an operating rod 16 pivoted at 17 to the stop 14 for projecting it to an operative position in which it overlies the rail 6, or for retracting it to an idle position in which the track is clear.

A cam 18 preferably of about semi-circular form, overlies the slotted end of the base member 5 and the abutment 9 and is provided with a hub 19 which passes slidably and turnably through the slot 8, being held against withdrawal from said slot by means of a bolt 20, washer 21 and nut 22, in the present disclosure. The cam 18 is provided with two arcuate converging cam surfaces 23 and 24 which extend between the outer end of the slide member 10 and the abutment 9, the surface 23 being in contact with said outer end of said slide member 10, and the surface 24 being in contact with the abutment 9. The outer end of the member 10 is preferably concavely curved as at 25 for contact with the surface 23, and it is preferable that this surface be concentric with the hub 19, whereas the surface 24 is spirally disposed with respect to said hub. However, this relation could of course be varied and the two cam surfaces still maintained in converging relation, to jointly act as a wedge when the cam 18 is turned, thereby relatively moving the hooks 7 and the member 10 into clamping relation with the rail 6 to hold the entire device in place thereon.

I prefer to provide the cam 18 with an upwardly projecting lug 26 to be struck with a hammer, axe, or piece of equipment to forcibly turn said cam to operative position in which it effects tight clamping of the device upon the rail. The same lug is of course usable in the same way when releasing the cam to detach the device from the rail. As the cam turns and the two members 5 and 10 relatively move into clamping position or released position, the cam 18 moves longitudinally of said member 5 and its hub 19 then slides in the slot 8. Since the pivot of the cam is thus free from direct attachment to either of the members 5 or 10, said pivot is relieved of strain which it would necessarily receive if the cam acted only against the member 10 and had its pivot directly secured to the base member 5.

Particular attention is invited to the rod 16 by means of which the stop 14 may be moved to and from operative position without endangering the person so moving said stop. Frequently the coal seam is only thirty-six inches high or less. This condition has necessitated the broadening,

lengthening and lowering of mine cars to increase their capacity and still permit them to operate in this low coal seam, until many of them overhang the track at the sides as much as eighteen 5 or twenty inches and clear the track only by four and one-half inches or even less. These overhanging low cars make it difficult to attach and operate most car stops and they present a real hazard to the worker in that he must lie 10 down and reach under the car to attach or adjust the stop. By providing the rod 16, however, extending to a safe distance, this difficulty and hazard are overcome as the stop can be operated while the worker is in a safe position without the 15 boundary of the car.

From the foregoing taken in connection with the accompanying drawing, it will be seen that a novel device has been provided for carrying out the objects of the invention. While details have 20 been disclosed which may be considered as preferred, attention is invited to the fact that variations may be made within the scope of the invention as claimed.

I claim:

- 25 1. A car stop comprising two clamping members connected for relative movement into and out of clamping engagement with a rail base, said members having opposed abutments spaced apart in the direction in which said members are relatively movable, a cam, means mounting said cam on one of said members for turning about an axis and for sliding movement in the aforesaid direction, said cam having two arcuate converging cam surfaces extending between said abutments, said arcuate surfaces contacting one with one of said abutments and the other with the other of said abutments, and a wheel stop mounted for projection and retraction on one of said members to overlie the rail when projected and to clear the rail when retracted.
- 30 2. A car stop comprising two clamping members connected for relative movement into and out of clamping engagement with a rail base, said members having opposed abutments spaced apart in the direction in which said members are relatively movable, one of said members being provided with a slot extending in said direction, a cam, means mounting said cam for turning about a vertical axis and for sliding movement in the aforesaid direction, said means having a portion 35 slidible in the aforesaid slot, said cam having two arcuate converging cam surfaces extending between said abutments, said arcuate surfaces contacting one with one of said abutments and the other with the other of said abutments, and a wheel stop mounted for projection and retraction on one of said members to overlie the rail when projected and to clear the rail when retracted.
- 35 3. A car stop comprising a base member to extend transversely under a rail and having a hook at one end to engage one edge of the rail base, a slide member upon and slidably connected with said base member to abut the other edge

of the rail base, said base member having an upstanding abutment in outwardly spaced relation with the outer end of said slide member, a cam overlying the end of said base member remote from said hook, means mounting said cam on said base member for turning about a vertical axis and for sliding movement in the direction in which said slide member is slidable, said cam having two arcuate converging cam surfaces extending between said outer end of said slide member and said abutment, said cam surfaces contacting one with said abutment and the other with said outer end of said slide member, and a wheel stop mounted for projection and retraction on said slide member to overlie the rail when projected and to clear the rail when retracted.

4. A car stop comprising a base member to extend transversely under a rail and having a hook at one end to engage one edge of the rail base, a slide member upon and slidably connected with said base member to abut the other edge of the rail base, said base member having an upstanding abutment in outwardly spaced relation with the outer end of said slide member, the end of said base member remote from said hook being provided with a slot elongated in the direction in which said slide member is movable, a cam overlying said slot and said abutment, means mounting said cam for turning about a vertical axis and for sliding movement in the direction in which said slide member is movable, said means having a portion slidible in the aforesaid slot, said cam having two arcuate converging cam surfaces extending between said outer end of said slide member and said abutment, said cam surfaces contacting one with said abutment and the other with said outer end of said slide member, and a wheel stop mounted for projection and retraction on said slide member to overlie the rail when projected and to clear the rail when retracted.

5. A car stop comprising a base member to extend transversely under a rail and having a hook at one end to engage one edge of the rail base, a slide member upon and slidably connected with said base member to abut the other edge of the rail base, said base member having an upstanding abutment in outwardly spaced relation with the outer end of said slide member, the end of said base member remote from said hook being provided with a slot elongated in the direction in which said slide member is movable, a cam overlying said slot and said abutment and having a downwardly projecting hub rotatable and slidible in said slot and held against withdrawal therefrom, said cam having two arcuate converging cam surfaces extending between said outer end of said slide member and said abutment, said cam surfaces contacting one with said abutment and the other with said outer end of said slide member, and a wheel stop mounted for projection and retraction on said slide member to overlie the rail when projected and to clear the rail when retracted.

DELMAR B. FINCH.
